Primary Examiner — Anhdao Doan*(74) Attorney, Agent, or Firm* — Wood, Herron & Evans, LLP**CLAIM**

We claim the ornamental design for a PCR multiwell plate and cap mat assembly, as shown and described.

DESCRIPTION

FIG. 1 is a top plan view of a PCR multiwell plate and cap mat assembly showing our new design;

FIG. 2 is a front view thereof with a portion in cross section;
 FIG. 3 is an enlarged view of the encircled area shown in FIG. 2;

FIG. 4 is a side view thereof;

FIG. 5 is a bottom plan view thereof;

FIG. 6 is a top perspective view thereof in a partially exposed position; and,

FIG. 7 is a top perspective view thereof.

1 Claim, 3 Drawing Sheets
